Primary Examiner — Barbara Fox*Assistant Examiner* — Dana K Weiland(74) *Attorney, Agent, or Firm* — EcoTech Law Group, P.C.(57) **CLAIM**

We claim the ornamental design for a touch screen display with hexagonal keys, as shown and described.

DESCRIPTION

The FIGURE is a front view of a touch screen display with hexagonal keys showing the new design. The broken line showing of a device depict environment. The remaining broken lines depict portions of the touch screen display with hexagonal keys. The broken lines form no part of the claimed design.
